Patented Nov. 27, 1917.

UNITED STATES PATENT OFFICE.

JOHAN F. FRITZ, OF PORTLAND, OREGON.

DRAINING APPARATUS FOR TUNNELS, &c.

1,247,812.

Specification of Letters Patent. Patented Nov. 27, 1917.

Application filed March 15, 1917. Serial No. 155,046.

To all whom it may concern:

Be it known that I, JOHAN F. FRITZ, a subject of the King of Sweden, who have declared my intention to become a citizen 5 of the United States, residing at Portland, in the county of Multnomah and State of Oregon, have invented a new and useful Draining Apparatus for Tunnels, &c., of which the following is a specification.

10 My invention relates to pumping machinery for the removal of water from tunnels, mines and ditches, especially while they are under construction.

The object is to provide a cheap, simple 15 and economically operated apparatus for said purposes.

When a tunnel is being constructed there is almost invariably the difficulty encountered that springs or other water will flow 20 into the tunnel or excavation and must be removed by pumping, for which steam or other engines are then employed. In my experience, however, I have found that usually some stream or creek of water can be 25 found not far from the work and utilized as motive power to operate the pump, especially if a special motor for utilizing a low water pressure is constructed and the right kind of water draining pipes and valves are 30 constructed for the purpose. My invention therefore comprises these means, as will presently be explained.

In the accompanying drawing;

Figure 1 is a side elevation of my apparatus about as near as it can be represented in a single view. Fig. 2 is a longitudinal vertical section of one of the swivel joints 63 of the exhaust pipe of the engine. Fig. 3 is an elevation of the left hand end of the 40 main structure shown in Fig. 1. Fig. 4 is a face view of either one of the radial arms 18, 18^a and 18^b in Fig. 1. Fig. 5 is a side view of the lower portion of the pulley 14 in Figs. 1 and 3. Fig. 6 is a top view of the 45 lever arm 46 to the right in Fig. 1.

Referring to the drawing by reference numerals, 1 designates suitable supports for the bed plate 2 of a water motor or water engine which comprises bearings 3, 3, 3 50 and 4 secured upon the bed plate, two water cylinders 5 secured underneath the bed

plate, pistons 6 in the cylinders and provided with piston rods 7 moving cross-heads 8 along guides 9 on the frame 3* holding the bearings or journal boxes 3. 65 From said cross-heads extend connecting rods 10, by which cranks 11 of the engine shaft 12 are operated. Said cranks are arranged in opposite radial directions and the shaft is provided with an efficient fly- 60 wheel 13 for carrying the cranks over their highest and lowest points. The shaft is also provided at one end with a pulley 14 for the transmission of power to other machinery (not shown). One spoke in the 65 pulley is provided with a slot 15 (see Fig. 5), any part of which may be occupied by a crank pin 16 which is movably secured in a slot 17, (see Fig. 4) in a radial arm 18 fixed on a short pump shaft 19, which is 70 thus rotated by the pulley; said shaft is thus journaled in the bearing 4 of the frame part 4* and provided at its outer end with another radial arm 18^a, having a slot 17 in which a pin 16^a is adjustably secured so that 75 the length of the stroke of two pump rods 20, 20^a may thus be altered to suit the available power of the engine.

Operated by the rods 20, 20^a are two pistons 22 in pump cylinders 23, which draw 80 water through the branches 24 of a pipe 25 and discharge it from spouts 26 into a race 27 which leads it to some place from which it can not flow back into the tunnel.

The pipe 25 is extended into the tunnel 85 and provided with several branches 25^a, 25^b, 25^c, one branch for each pool or pit in which the water is gathered. In the drawing the branch 25^a represents any of the other branches by being shown as extending into the water 29, and is provided with a valve 30, operated by a lever 31 pivoted at 32 and provided with a float 33, so that whenever the water is pumped away so that the float falls down to a certain point, its 90 lever closes the valve and thus prevents air passing in through the valve and break the suction in the pipe 25 which may yet be needed to draw water from other water pockets along the pipe line.

The water that operates the engine is 100 carried from the highest point obtainable.

or necessary through a pipe 34 into a cylindrical chamber 35 in which a two-headed slide valve 36, 36^a is fixed on a valve rod 37, and controls the intake and outlet ports 5 38 in the lower ends of the cylinders 5. The valve rod 37 slides in stuffing boxes 39 and carries upon its cushions 40 which by contacting with the stuffing boxes stop the quick movement of the slide valve, the cushion being retained on the rod by nuts or collars 41, 42. In the collar or head 42 is a pin 43, which is engaged by a fork 44 of a bell crank lever 45—46, which is pivoted at 47 to base 2 and has its arm 45 provided 10 with a pin 48 from which a spring 49 extends to a pin 50 in a frame post 51. The other arm 46 of the lever has its end 52 forked (see Fig. 6) so as to straddle the vertical rod 53, which is guided to slide in 15 bearings 54, 55; the upper end of the rod is jointed at 56 to a connecting rod 57, which is operated by a pin 58, that is adjustable to any point in the slotted arm 18^b on the engine shaft.

25 Adjustably secured by set screws on the rod 53 are two collars, 59 and 60, which by means of intermediate compression coil springs, 61 62, on the rod act on the lever 46 to throw it alternately upward and downward.

Secured to the end of the slide chamber 35 by swivel joints 63 (see Fig. 2) are branches 64 of a water exhaust or discharge pipe 65, which has its free end submerged 35 in water 66 in a tank 67, or a water pool in the ground will serve the same purpose, namely to prevent air from getting into the pipe branches and the valve chamber. It will be understood that where the conditions 40 permit it the pipe 65 should be made as long as possible and directed downwardly so as to create suction which helps to pull the pistons of the engine downward after the water has driven each of them in its 45 turn upward.

In further describing the operation it will be understood that in this as in all water engines the slide valve must move quickly and then rest while each cylinder is alternately one filled and the other emptied. To accomplish this the spring 49 tends at all times to throw the lever arm 45 and thereby the valve rod 37 in one direction or the other and to hold the rod with one of the cushions 55 40 against one of the stuffing boxes 39, just as soon as the spring is swung by the arm 45 to either side of the fulcrum 47; and the bringing of the arm to and slightly beyond its plumb down position is also accomplished quickly by the expansion of each spring 61, 62, after it has been compressed by the collar 59 or 60, as the case may be. Experiments have demonstrated that where the fall of the water is so limited that it is

impractical to use a turbine or other water-wheel this form of engine can be run by such fall and do the necessary pumping, and that at a comparatively light cost of production and maintenance of the device.

What I claim is:

1. In an apparatus for the purposes stated, a pipe line arranged to draw water from one or more places, a pump connected with the highest part of the pipe line, and a water engine running the pump, said engine having a crankshaft, cylinders and piston therein operatively connected with the crank shaft, a valve chamber, a slide valve in the chamber operatively associated with the crank shaft and arranged to admit water into and out from one end of each cylinder in alternative order, a water head pipe leading water into said valve chamber and an exhaust pipe carrying away the water from the cylinders, said exhaust pipe extending downwardly and having its outlet end submerged in water during the running of the engine.

2. In an apparatus for the purposes stated, a pipe line arranged to draw water from one or more places, a pump connected with the highest part of the pipe line, and a water engine running the pump, said engine having a crank shaft, a valve chamber, a slide valve in the chamber operatively associated with the crank shaft and arranged to admit water into and out from one end of each cylinder in alternative order, a water head pipe leading water into said valve chamber and an exhaust pipe carrying away the water from the cylinders, said exhaust pipe extending downwardly and having its outlet end submerged in water during the running of the engine, said exhaust pipe having swivel joints admitting its end to be freely swung downward at any required incline to reach into the water that is to cover its outlet end.

3. In an apparatus for the purposes stated, a pipe line arranged to draw water from one or more places, a pump connected with the highest part of the pipe line, and a water engine running the pump, said water engine having a crank-shaft with a flywheel thereon, cylinders and pistons, and operative connection between the pistons and the crank shaft, a slide valve admitting the driving water to and from the cylinders, cushions on the rod of the slide valve arranged to stop the valve quickly with a minimum noise, operative connection between the crank shaft and the valve rod; said operative connection comprising a cranklike contrivance on the engine shaft, a reciprocating rod operated thereby and having two collars, a bell crank lever fulcrumed at its angle and having one arm operatively connected with the valve rod, the

other arm having a forked end straddling the reciprocated rod intermediate the collars on it, a compressible spring encircling said rod between each collar and the adjacent 5 side of the fork, and a contraction coil spring normally crossing the fulcrum of the lever

and having one end connected to the lever arm operating the valve rod, and its other end secured to the frame work of the structure.

10

In testimony whereof I affix my signature.
JOHAN F. FRITZ.
